WELL SINKING MACHINE.

No. 394,719.

Patented Dec. 18, 1888.

UNITED STATES PATENT OFFICE.

CHESTER A. OVERTON AND OSCAR E. INGERSOLL, OF BLISS, NEBRASKA.

WELL-SINKING MACHINE.

SPECIFICATION forming part of Letters Patent No. 394,719, dated December 18, 1888.

Application filed November 26, 1887. Serial No. 256,210. (No model.)

To all whom it may concern:

Be it known that we, CHESTER A. OVERTON and OSCAR E. INGERSOLL, both of Bliss, in the county of Wheeler and State of Nebraska, 5 have invented a new and Improved Well-Sinking Machine, of which the following is a full, clear, and exact description.

The object of our invention is to provide a new and improved well-sinking machine 10 which is simple and durable in construction and permits of sinking a well very rapidly.

The invention consists of a specially-constructed sliding support for the tubing of a drilling-tool and a perforated pipe forming 15 part of the boring-tube and covered by a shell adapted to be cut and raised after the well is sunk to the proper depth.

The invention also consists of certain parts and details and combinations of the same, as 20 will be fully described hereinafter, and then pointed out in the claims.

Reference is to be had to the accompanying drawings, forming a part of this specification, in which similar letters of reference indicate 25 corresponding parts in all the figures.

Figure 1 is a perspective view of our improvement. Fig. 2 is an enlarged side elevation of the drilling-tool and connections. Fig. 3 is an end elevation of the same with the 30 shell drawn upward. Fig. 4 is an enlarged perspective view, partly in section, of the tubing-support.

Our improved well-sinking machine is provided with a derrick, A, preferably of the 35 construction shown in Fig. 1, in which it is composed of three posts, B, B', and B'', of suitable length and connected together on the top. The two posts B and B' are provided with the rungs B³, so as to form a ladder to 40 enable the operator to climb up to the top of the derrick whenever necessary. One of the rungs B³ is connected by a horizontal rod, B⁴, with the post B'', and the said rod B⁴ extends about the middle of the derrick A.

On the rod B⁴ and the upper end of the post B'' is secured a vertical guide-rod, C, 45 preferably square in cross-section, as shown in Figs. 1 and 4. On the guide-rod C is held to slide the tubing-support D, consisting of 50 the bands D' and D'', encircling the guide-

rod C and connected with each other in front by the vertical arm D³, provided with the lugs D⁴, supporting a pin, D⁵, on which is hung a hook, E', secured to one end of a rope, E, extending upward and passing over a sheave, 55 F, held on the upper end of the derrick A. The rope E, after passing over the sheave F, extends downward and is wound upon a drum of a windlass, G, of any approved construction, and mounted on the posts B and B' 60 near the lower ends.

On the bolt D⁵ on the sliding support D is also held a clevis, H, passing around a pipe, I, having at its upper end the bent part I', connected with one end of a flexible tube, J, 65 leading to a force-pump, K, of any approved construction. The pipe I passes through a cap, L, screwing onto a short pipe or cylinder, L', screwing onto a coupling, L'', on which is also secured the upper end of the well-tub- 70 ing N.

On the extreme lower end of the pipe I is formed a flange or collar, I², held between the upper edge of the tubing N and the lower edge of the cylinder L'. The latter, as well 75 as the cap L, are filled with a suitable packing material, L³, which surrounds the pipe I and rests on the collar L². The pipe I is thus held to turn freely in the cap L and discharges into the tubing N, at the same time preventing a leaking of the water from the tubing 80 upward through the cylinder L' and cap L on account of the packing L³.

The lowest section of the boring-tubing N is formed by a perforated pipe, P, having a 85 wire-gauze, P³, on its inner side and an imperforate shell on its outer side, to be presently described. The lower end of the drilling-tube section or pipe P is connected by the coupling P³ with the tool-supporting pipe Q, 90 having in its lower end a diametrical slot, Q', into which fits the shank R' of the drilling-tool R, secured by a bolt, S, to the said lower end of the supporting-pipe Q.

The drilling-tool R is provided at its lower 95 end with the cutting-edges R², diverging slightly upwardly and being bent in opposite direction, as shown in Fig. 3.

When the well is being sunk, then the perforated water-inlet pipe P is covered on its 100

outside by a closely-fitting shell, T, preferably of tin, and provided on its upper end with a funnel, T', commencing at its lowest smallest end, a short distance below the bottom end 5 of the coupling N², which prevents an upward movement of the shell T, as the latter is somewhat less in diameter than the coupling N². On the upper end of the funnel T' is held a ring, T², and on the lower edge of the shell T 10 are held diametrically opposite each other the hook-knives U, secured to the end of a wire or rope, U', extending upward between the shell T and the pipe P. The rope U' passes into an aperture, N³, formed in the upper end 15 of the lowest section, N', of the tubing N, and then horizontally through the section N' and out of a second aperture, N⁴, placed opposite the aperture N³. The part U² of the wire or rope U' in the section N' can be engaged by 20 a hook, V', secured to a rope, V, passed down the tubing N from the upper end on the surface of the ground.

The operation is as follows: A section of the tubing N is screwed onto the coupling L², 25 and is then raised into a vertical position by operating the windlass G, so that the rope E is wound up on the drum of the windlass G. The tubing-support D is thus caused to slide upward on the guide-rod C until the section 30 hangs vertical, and can now be secured to the top section of the tubing already in the ground. The operator now starts the force-pump K, so that the water passes up through the flexible tube J into the swiveled pipe I, 35 and from the latter flows into the tubing N. The latter is now turned by means of tongs or wrenches, so that the drilling-tool R cuts with its cutting-edges R² the ground which is loosened by the water passing down the tubing 40 N and the tool-supporting pipe Q and out of the latter at its lowest end onto the drilling-tool and the ground, the shell serving to prevent the water from passing out through the lower section or pipe, P, of the tubing. When 45 the well is sunk to the proper depth, then the operator lets the rope V, carrying the hook V', down in the tubing N until the hook engages the part U² of the wire or rope U'. The operator then pulls the rope V upward through 50 the apertures N³ and N⁴, so that the cutting-hooks U, held on the lower edges of the shell T, cut the latter in two parts, as illustrated in Fig. 3. The hooks U in their upward cutting motion finally engage the ring T², which resists cutting, so that a further pull on the rope 55 V lifts the two halves of the shell T upward and above the water-inlet pipe P, so that the apertures P' in the latter are uncovered, and water from the water-vein can freely pass 60 into the said pipe and up through the tubing N to the surface of the ground.

Having thus fully described our invention, we claim as new and desire to secure by Letters Patent—

65 1. In a well-sinking machine, the combination of a perforated section or pipe of the

drill-tubing with a tubular shell closing said perforations and adapted to be forced from over the perforations from above ground, substantially as set forth. 70

2. In a well-sinking machine, the combination, with a perforated drill-tubing section or pipe, of a shell held on the outside thereof and hook-knives engaging the lower edge of the said shell and adapted to cut the latter, 75 substantially as shown and described.

3. In a well-sinking machine, the combination, with a perforated drill-tubing section or pipe, of a shell held on the outside thereof, hook-knives engaging the lower edge of the 80 said shell and adapted to cut the latter, and a wire or rope supporting the said hook-knives and adapted to be pulled upward, substantially as shown and described.

4. In a well-sinking machine, the combination, with the tubing having a perforated section or pipe held on its lower end, of a shell surrounding the said section or pipe, hook-knives held on the lower edge of the said shell, a wire or rope connected by its ends 90 with the said hook-knives and extending upward and through the lower section of the tubing, and a rope carrying a hook passed down the tubing and adapted to engage the said wire or rope, substantially as shown and 95 described.

5. In a well-sinking machine, the combination, with the tubing having a perforated section or pipe held on its lower end, and means for closing the perforations to prevent the 100 exit of the hydraulic column, of a tool-supporting pipe held on the lower end of the said perforated pipe and provided with a diametrical slot, a drilling-tool having the diverging cutting-edges R², projecting beyond the sides 105 of its supporting-pipe and engaging with its shank the said slot, and a bolt for fastening the said drilling-tool immovably in said slot, substantially as shown and described.

6. In a well-sinking machine, the combination, with the well-tubing, of a cylinder connected with the upper end of the well-tubing, a cap held on the upper end of the said cylinder, a pipe extending through the said cap and cylinder, provided at its lower end with a 115 collar held between the lower edge of the cylinder and the upper edge of the said well-tubing, and a packing surrounding the said tube in the said cylinder and cap, substantially as shown and described. 120

7. In a well-sinking machine, the combination, with the well-tubing, of a cylinder connected with the upper end of the well-tubing, a cap held on the upper end of the said cylinder, a pipe extending through the said cap 125 and cylinder, provided at its lower end with a collar held between the lower edge of the cylinder and the upper edge of the said well-tubing, a packing surrounding the said tube in the said cylinder and cap, a flexible tube 130 connected with the outer bent end of the said pipe, and a force-pump connected with the

said flexible tube, substantially as shown and described.

8. The combination, in a well-drilling machine in which hydraulic force is used, with the drill-tubing having perforations just above the tool, of a vertically-movable severable sleeve closing the said perforations

against the outflow of the hydraulic column, substantially as set forth.
